[57] **CLAIM**

The ornamental design for an end attachment for watch band, as shown and described.

DESCRIPTION

FIG. 1 is a perspective view of an end attachment for watch band showing my new design;

FIG. 2 is a perspective view thereof from the side opposite that shown in FIG. 1;

FIG. 3 is a top plan view thereof;

FIG. 4 is a bottom plan view thereof;

FIG. 5 is a side elevational view thereof;

FIG. 6 is a side elevational view thereof from the side opposite that shown in FIG. 5; and

FIG. 7 is an end elevational view thereof, viewed from the right in FIG. 5, the end elevational view opposite that shown in FIG. 7 being the mirror image thereof.

FIG.1
